UNITED STATES PATENT OFFICE.

MARION F. YOUNG, OF PUEBLO, COLORADO.

ELECTRICAL SWITCH.

1,052,550.

Specification of Letters Patent. Patented Feb. 11, 1913.

Application filed April 19, 1911. Serial No. 622,002.

To all whom it may concern:

Be it known that I, MARION F. YOUNG, a citizen of the United States, residing at Pueblo, in the county of Pueblo and State 5 of Colorado, have invented certain new and useful Improvements in Electrical Switches, of which the following is a specification.

This invention relates to electrical switches designed for use on trolley or underground 10 electric railways, and one of the principal objects of the invention is to provide simple, reliable and efficient means for throwing the switch points by automatic means whenever desired by the motorman.

Another object of the invention is to provide an electric switch in which the mechanism for operating the switch is entirely 15 inclosed in a water tight casing located at a suitable point adjacent to the track, said 20 casing containing a motor which is operated at the will of the motorman on the car for throwing the switch points.

Still another object of the invention is to provide means for operating switches electrically whenever desired by the motorman, 25 said means comprising inner rails located between the ordinary track rails, contact wheels connected to the car, an electric motor, means on the car for raising and lowering 30 the contact wheels and electrical connections between the motor, the controller on the car, the car wheels and the contact wheels.

These and other objects may be attained 35 by means of the construction illustrated in the accompanying drawings, in which,

Figure 1 is a side elevation of a portion 40 of a trolley car showing means for operating the contact wheels made in accordance with my invention. Fig. 2 is a plan view showing the motor casing in section and the electrical connections for operating the switch points. Fig. 3 is a front end elevation of 45 the car showing the contact rails and the track rails and switch points in section. Fig. 4 is a view in elevation and partial section showing the mechanism for throwing the switch points.

Referring to the drawings the numeral 1 50 designates a trolley car of the overhead trolley type and it will be understood that my invention may be used in connection with other types of electric cars with slight modifications in the manner of making the electrical connections.

The numeral 2 designates the main track

rails, 3 the switch points, 4 the car wheels, 5 the trolley pole and 6 the main line wire. These elements or parts may be of the usual or any suitable construction. Contact rails 6' are secured to the ties 7 between the track rails at a point near the switch for making the necessary connections for operating the motor and switch points. The contact rails 6' may be formed of T-iron or angle bars. 65 Contact wheels 8, preferably provided with grooves to fit the contact rails 6' are journaled on the ends of an axle 9, said ends being insulated from each other as shown at 30, Fig. 2, to which axle is connected a 70 bar 10, said bar being pivoted underneath the car 1 and provided with a lever 11 for raising and lowering the contact wheels 8, said lever being operated by means of a push pin 12 extending through the platform near 75 the controller 13. The switch points 3 are connected together by a rod 14 in order that both switch points may be operated together.

A water tight box or casing 15, located at any convenient point near the switch contains 80 an electric motor 16. On the main shaft of the motor is a pinion 17 in mesh with a gear wheel 18 mounted on a shaft 19. One of the spokes of the gear wheel 18 is provided with a pin 20. A bar 21 is provided 85 with pivoted stops 22 disposed in opposite relation on said bar 21, said stops being pivoted at 23 to the bar and provided with limiting pins 24 which prevent the movement of the stops 22 beyond a horizontal position. Springs 25 are secured to the bar 21 and bear against the stops 22 for holding them down in position in the path of the pin 20. Pivotal connected to the bar 21 is a two armed lever 26 pivoted at 27 90 to one of the ties 7. The upper end of the lever 26 is pivotally connected to a link 28 secured to one of the switch points 3. The electrical connections are shown in Fig. 2 and when established by means of the contact wheels 8 with the contact rails 6' the current passes through one of the wires to one of the contact wheels, through the wheel to one of the rails 6', through the rail and the wire connected to its end to the motor, 100 through the motor out through the wire connected to the other rail 6', through the rail to the other contact wheel and through this wheel and the wire connected to it back to the controller.

When the motorman desires to switch his car or train he permits the wheels 8 to drop

- which establishes connections with the motor and rotates the pinion 17 and the gear wheel 18. When the pin 20 on the gear wheel 18 comes into contact with the stop 22 it pushes the bar 21 toward the left in Fig. 4 and operates the switch points. The motor may run some time after the switch points have been thrown, but the pin 20 will elevate one of the stops 22 against the tension of this spring 25, said pin coming in contact with the end of the other stop 22 moves the lever 21 slightly. The pin 20 moves the bar 21 a sufficient distance to pass underneath the stop 22.
- 15 From the foregoing it will be obvious that my electrical switch is of simple construction, cannot readily get out of order, is automatic in use, can be quickly operated, and can be installed at slight cost.
- 20 I claim:
1. An electric switch comprising contact rails, contact wheels on the car, means for raising and lowering the contact wheels, an electric motor confined within a box or casting, a pinion on the shaft of the motor, a gear wheel provided with a stop pin, a bar provided with pivoted stops, springs for holding said stops within the path of the

stop pin, and connections between said bar and the switch points.

2. A switch for electrical lines comprising contact rails, contact wheels mounted under the car, means for raising and lowering said contact wheels, an electric motor, a pinion on the shaft of the electric motor, a gear wheel in mesh with said pinion, said gear wheel having a stop pin thereon, a bar provided with pivoted stops disposed in the path of the stop pin, springs for holding said stops in the path of the pin, a lever connected to said bar, and a link connected to said lever, the said link being attached to one of the switch points.

3. In an electric switch, the combination of an electric motor, a gear wheel operated by the motor, a stop pin on the gear wheel, a bar provided with pivoted stops disposed in the path of the stop pin, and means connected to the bar for operating the switch point when the motor is operated.

In testimony whereof I affix my signature in presence of two witnesses.

MARION F. YOUNG.
